HAND REGULATING VALVE FOR ROTATION MOTORS

Filed March 23, 1922

2 Sheets-Sheet 2

UNITED STATES PATENT OFFICE

CHARLES C. HANSEN, OF EASTON, PENNSYLVANIA, ASSIGNOR TO INGERSOLL-RAND COMPANY, OF JERSEY CITY, NEW JERSEY, A CORPORATION OF NEW JERSEY.

HAND-REGULATING VALVE FOR ROTATION MOTORS.

Application filed March 28, 1922. Serial No. 545,891.

To all whom it may concern:

Be it known that I, CHARLES C. HANSEN, a citizen of the United States, and a resident of Easton, county of Northampton, and State of Pennsylvania, have invented a certain Hand-Regulating Valve for Rotation Motors, of which the following is a specification, accompanied by drawings.

This invention relates to fluid actuated rock drills of the hammer type, but more particularly to a hand operated valve for regulating the supply of motive fluid to the rotation motor of such a machine.

In my co-pending application, Serial No. 514,816 filed November 12, 1921, I have disclosed an automatic and manually adjustable regulating valve for rotation motors, but the object of the present invention, while in some respects similar, is to procure a simpler manually adjustable device by means of which the supply to the motor may be increased when desired, or in one modification, shut off entirely or regulated between these limits. Another object of the invention is to enable these results to be accomplished by means of a combined rotary and longitudinally movable valve, which automatically returns to normal position after having been temporarily moved for a given adjustment.

The drawings illustrate so much of a rock drill of the hammer type, as will serve to make the invention clear, and

Figure 1 is a side elevation partly in longitudinal section of a rock drill having one form of my regulating valve applied thereto,

Figure 2 is a detail transverse sectional view through the motor on the line 2-2 of Figure 1,

Figure 3 is a detail longitudinal vertical sectional view similar to a portion of Figure 1, with the valve moved inwardly to accelerate the motor,

Figure 4 is a detail view similar to Figure 3 of a modified form of regulating valve having both longitudinal and rotary movement for adjusting purposes.

Figures 5, 6 and 7 are detail transverse sectional views on the lines 5-5, 6-6 and 7-7 respectively of Figure 4, with the valve in starting or normal running position, and

Figures 8, 9 and 10 are similar transverse sectional views with the valve closed.

Referring to the drawings, the machine

comprises a cylinder A, having a front head B provided with the rotation sleeve C through which the drill steel D extends in position to receive the impact of the reciprocating piston hammer E. A fluid actuated rotation motor of the gear type having the gears F, is mounted in the back end portion G of the cylinder, and the back head H is provided with a valve chest J for the rotation motor regulating valve. The parts of the machine are secured together by the usual through bolts K. One of the gears F is provided with a spindle F' having a pinion G' within the front head B meshing with a gear H' on the rotation sleeve C, for imparting rotation to the drill steel D.

Motive fluid is supplied to the machine through the inlet L and passing from the usual throttle valve O, enters the valve chest J through the passage P. From the valve chest, the motive fluid passes through the port Q and passage R to the rotation motor, exhausting from the motor through the exhaust ports S into the exhaust space T which is open to atmosphere at each side between the back end portion G of the cylinder and the cylinder A.

The valve structure in the valve chest or casing J comprises a cylindrical valve cage U removably secured in said casing as by means of the screw threads V, and affording communication between the fluid supply passage P and the motor. Within the cage U is located a valve stem W having an inner valve head X, a reduced neck Y and a shank Z movable longitudinally in the cage. A spring a is adapted to be compressed between the cage and the handle or outer head b of the valve stem, for retracting the valve after it has been pushed or moved inwardly to increase the supply of motive fluid to the motor, and a stop limiting the movement of the valve is provided in the form of a pin c, extending transversely through the cage and through a slot d in the shank Z of the stem.

The cage U as shown is provided with a supply port e in the side wall at the inner end of the cage, communicating with the bore of the cage, and the valve head X normally lies at rest in the cage, forwardly of said supply port e, as indicated in Figure 1 of the drawing. The valve head X, however, is of such construction that it permits a con-

tinuous flow of motive fluid to the motor through the cage, in this instance the valve head being of less diameter than the bore of the cage, so that fluid may pass continuously around the head as indicated by the arrows in Figure 1, when the throttle valve O is open. The supply to the motor is increased by moving the stem and valve head inwardly towards the motor to the position indicated in Figure 3, for instance, in which the valve head X is moved beyond the inner end of the cage which permits a greater flow of motive fluid to the motor. Upon removing the fingers or hand from the outer-head b of the stem W, the retracting spring a returns the valve to the position indicated in Figure 1. In order to seal the joint between the back head H and the motor casing G a metallic sleeve or thimble f is provided between these parts, connecting the port Q in the back head with the passage R in the motor casing, and a rubber packing g is inserted over the thimble f and adapted to be compressed between the back head H and the motor casing G when the through bolts K are tightened.

In the modification of the invention, shown in Figures 4 to 10 inclusive, the valve chest or casing J is provided as before with a removable valve cage U' having therein a rotatable and longitudinally movable valve stem W' provided with a head X' and a reduced or recessed portion h rearwardly of the head. A coiled spring a' located between the outer knurled head b' of the valve stem and the valve cage, has one end j secured to the head and the other end k secured to the cage, so that the spring a' not only acts as a retracting spring after the stem has been moved inwardly, but if the stem is rotated in a direction to wind the spring, the valve and valve stem will be automatically returned or rotated in the opposite direction, to normal position, when the hand or fingers are removed from the knurled head b'. A stop in the form of a pin c' passes through the cage and through the recessed portion o of the valve stem for limiting the longitudinal movement of the stem. This stop pin c' also limits rotary movement of the valve stem through an angle of about 180° as will be apparent. The wall of the cage is provided with a supply port e' near its inner end and the valve head X' is formed with a port p through which motive fluid continually passes to the motor when the valve is in normal open or running position, as indicated in Figure 4 and in the detail views shown in Figures 5, 6 and 7.

By simply pushing or forcing the valve stem W' and valve head X' inwardly, the flow of motive fluid to the motor is increased, since the valve head X' will be carried inwardly beyond the inner end of the

cage U' and more fluid may flow to the motor.

With the valve in the position indicated in Figure 4, illustrated in detail in Figures 5, 6 and 7, motive fluid is continually passed to the motor and this is the normal or running position. By rotating the valve through an arc of about 180° as indicated in detail in Figures 8, 9 and 10, motive fluid is entirely shut off from the motor. At intermediate rotary positions of the valve, the recessed portion h of the valve stem permits more or less fluid to pass to the motor as desired, and the valve will always be automatically returned to normal position by releasing the spring a'.

I claim:

1. In a fluid actuated rock drill of the hammer type, the combination of a rotation motor and a valve for controlling the supply of fluid to said motor, said valve comprising a casing, a cylindrical valve cage removably secured in said casing and affording communication between the fluid supply and the motor, a valve stem having an inner valve head, a reduced neck and a shank movable longitudinally in said cage, a spring for normally retracting the stem, and a stop limiting the movement of the stem, the valve head permitting a continuous flow of motive fluid to the motor through the cage, and the supply to the motor being increased by moving the stem and valve head inwardly towards the motor.

2. In a fluid actuated rock drill of the hammer type, the combination of a rotation motor and a valve for controlling the supply of fluid to said motor, said valve comprising a casing, a cylindrical valve cage removably secured in said casing and affording communication between the fluid supply and the motor, a valve stem having an inner valve head, a reduced neck and a shank movable longitudinally in said cage, a spring for normally retracting the stem and a stop limiting the movement of the stem, the valve head being of less diameter than the bore of the cage, whereby fluid may continually be applied to the motor through the valve and the supply may be increased by moving the stem and the valve head inwardly towards the motor to permit more fluid to flow past the reduced neck on the spindle.

3. In a fluid actuated rock drill of the hammer type, the combination of a rotation motor and a valve for controlling the supply of fluid to said motor, said valve comprising a casing, a cylindrical valve cage removably inserted in the casing and having a longitudinal bore communicating with the inlet of the motor, a supply port in the wall of said cage at its inner end, a valve stem movable longitudinally in said cage and having a valve head and a reduced

neck at its inner end, a retracting spring and a stop for the valve stem, the valve head being of less diameter than the bore of the cage, and normally lying in the bore of the cage forwardly of the said supply port, whereby fluid is continuously supplied to the motor and the supply is increased by

forcing the valve stem inwardly towards the motor to carry the valve head beyond the inner end of the cage.

10

In testimony whereof I have signed this specification.

CHARLES C. HANSEN.
